UNITED STATES PATENT OFFICE.

JOHN A. EKELUND, OF MINNEAPOLIS, MINNESOTA.

BALL GAME APPARATUS.

Application filed June 10, 1927. Serial No. 197,859.

This invention relates to toy ball game apparatus and particularly to improvements on my "toy baseball game apparatus" patented by me on May 24, 1910, Patent No. 959,427.

5 The object of this invention is to provide certain new improvements on my apparatus described and claimed in the above entitled patent.

To this end the invention consists in the 10 novel devices and novel combinations of devices defined in the claims and described in the following specification made in connection with the accompanying drawings, wherein like reference characters refer to the 15 same or similar parts throughout the various views and, in which,

Fig. 1 is a plan view of the assembled apparatus ready to be used for playing a game of ball;

20 Fig. 2 is a vertical section taken on the line 2—2 of Fig. 1, as indicated by the arrows and showing the playing field with the other parts removed;

Fig. 3 is a vertical section taken through 25 the playing field and illustrating the pitcher and pitching mound in right side elevation, certain of the movable parts being shown in one position in full lines and in another position in dotted lines;

30 Fig. 4 is a vertical section taken through the playing field and showing the pitcher and pitching mound in rear end elevation;

Fig. 5 is a horizontal section taken on the line 5—5 of Fig. 3, as indicated by the arrows;

35 Fig. 6 is a top plan view of the catcher detached from the playing field;

Fig. 7 is a view in side elevation of the detached catcher illustrating certain of the parts in full lines in one position and in dotted lines in another position;

40 Fig. 8 is a view in side elevation illustrating the batter detached;

Fig. 9 is a horizontal section taken on the line 9—9 of Fig. 8 as indicated by the arrows;

45 Fig. 10 is a plan view looking down on the batter and catcher plate with the batter and catcher removed, certain of the movable parts being illustrated in one position in full lines and in another position in dotted lines;

50 Fig. 11 is a view in side elevation of the parts illustrated in Fig. 10;

Fig. 12 is a plan view of one of the fielders;

Fig. 13 is a view in side elevation of a fielder;

55 Fig. 14 is a view in side elevation of a base runner;

Fig. 15 is a view in front elevation of a base runner, and

Fig. 16 is a perspective view of a type of ball that may be used.

Referring to the drawings, a square board 20 is illustrated having secured thereto at its upper side a baseball playing field 21 and having marginal upwardly extending flanges 22 above the playing field 21 for confining the ball in its movements upon the playing field. The playing field 21 is preferably composed of sheet material and has a plurality of up-pressed ribs 21^a provided therein which define a baseball diamond 23, foul space 24 and a baseball outfield divided into a plurality of pockets 25. The diamond 23 has bases stamped or otherwise formed thereon, the respective bases having the characteristics 1, 2, 3 and 4 thereon to indicate first, second and third base and the home plate respectively. Pockets 25 have various indicia thereon such as 1 B. H., 2 B. H., 3 B. H. and H. R., indicating respectively one base hit, two base hit, 75 three base hit and home run, while the diamond 23 has marked thereon a characteristic such as 1 B. H. indicating one base hit. The said characteristics are adapted to designate the type of hit that a batter has made when the ball lights in one of the pockets 25 or on the diamond 23 after having been struck by the batter. If desired, certain of the pockets 25 may be provided with various other types of designating characteristics to indicate other possible plays in a game of baseball.

Secured to the playing field 21 at points on a number of the pockets 25 are the headed studs 26. Infield and outfield players 27 are adapted to be secured to the studs. Each player 27 is formed preferably from sheet material and is provided with a flat bottom portion, upwardly and rearwardly inclined back portion, side and front flanges and a keyway in its bottom portion whereby the player can be detachably secured to a headed stud 26. 90 Preferably seven of the players 27 are provided to correspond to the number of infielders and outfielders in a game of baseball and each of the players 27 have preferably stamped thereon the word "Out" to indicate that the batter is out when a ball is caught in the pocket formed by the player. A bench 28 is stamped out or otherwise formed in the foul space 24, and base runners 29 are normally adapted to rest on the bench 28 when not situated on one of the bases. Each of the base runners 29 is preferably formed from

110

sheet material and has a horizontal bottom portion and an inclined portion shaped to form a toy figure.

A pitching mound 30 of channel shape is secured as by screws to the playing field 21 immediately behind second base so that the central portion of the channel will stand upwardly from the playing field, the said central portion being provided with a small rectangular aperture 30^a adjacent its rear end. A pitcher base plate 31 is pivoted by the pivot 32 to the pitching mound 30 adjacent its rear end and the plate is provided with an arcuate slot 31^a adjacent its forward end through which a bolt 33 extends, the said bolt extending through the mound 30 and having a co-operating nut therebelow. A washer is provided between the head of the bolt 33 and the plate 31. By unloosening the bolt 33 and swinging plate 31 about its pivot 32, the plate may be set at various angles with the mound 30, whereupon by tightening the bolt 33 the plate may be secured in a desired position in respect to the mound. Plate 31 has a portion 31^b struck up therefrom at the left side to form a latch with which a hook 34 pivoted on the pivot 32 is adapted to co-operate. An irregular shaped opening 31^c is provided in the plate 31 and a small rectangular opening 31^d is cut adjoining the opening 31^c and approximately alining with the opening 30^a to form a shoulder 31^e, the use of which will be hereinafter described. An angular pitcher securing bracket 35 having an irregular shaped horizontal flange adapted to releasably fit within the irregular shaped opening 31^c in plate 31 and to rest on top of the pitching mound 30 is provided.

The hook 34 is adapted to be swung over the horizontal flange of bracket 35 to releasably secure the same to plate 31. A bolt 36 extends through the vertical flange of bracket 35 and has pivoted thereon the body of an upstanding toy pitching figure formed from the two plates 37 and 38. Bolt 36 is of considerable length and carries between its nut and the plate 37 a sleeve 39 about which a coiled torsion spring 40 extends. The spring 40 has its lower end hooked over a horizontal arm 35^a formed on the vertical flange of bracket 35 and the other end of the spring is held by one of a series of spaced up-struck tabs 37^a formed in plate 37. The torsion spring 39 is adapted to act to exert resilient tension on the pitcher body to carry the same from a rearward position as indicated in full lines, Fig. 3, to a forward position abutting the arm 35^a as indicated in dotted lines, Fig. 3. A pitching arm 41 of angular shape and having a square box like ball carrying hand is secured to the plates 37 and 38 between the same by means of a bolt 42 carrying a wing nut. By means of the wing nut, the arm 41 may be loosened or tightened in respect to plates 37 and 38 to

permit the arm being raised or lowered to vary the position of the same. A lever 43 is pivoted at its forward end to the bottom of the plates 37 and 38 and is provided with a tooth 43^a adapted to drop by gravity into opening 31^a to engage with the shoulder 31^e when the pitcher is rearwardly swung to the position indicated in full lines Fig. 3. The tooth 43^a of lever 43 may be released from engagement with the shoulder 31^e by means of a trigger 44 pivoted to an upstanding arm 31^b at the rear end of plate 31. A ball 45 of cubular shape having rounded corners is provided which is adapted to be carried by the hand formed in the pitching arm 41 and to be pitched straight forwardly from the hand by the pitcher. Considering the pitcher parts to be in the position indicated in full lines, Fig. 3, with the tooth 43^a of lever 43 engaging shoulder 31^e and the ball 45 carried by pitching arm 41, as trigger 44 is pressed to release tooth 43^a from shoulder 31^e, the torsion spring 40 will carry the figure forwardly to the dotted position Fig. 3, whereupon as the plates 37 and 38 strike the arm 35^a the ball will be projected into the air. By properly adjusting the angular position of the plate 31 with the pitching mound 30, the pitcher can be adjusted so that the ball as thrown will be carried directly over the home plate. By raising or lowering the arm 41 the pitcher can be adjusted so that the height of the ball as it is thrown over the home plate will be such that a batter to be hereinafter described can strike the same. By engaging the upper end of torsion spring 40 with different tabs 37^a greater or less tension can be placed on the spring thereby causing the ball to move faster or slower, as the same is pitched.

A catcher and batter plate 46 is secured to the foul portion 24 of the playing field 21 to extend at one side of and behind the home plate of the diamond. A lug 47 is vertically pivoted on plate 46 immediately behind the home plate and the said lug has an upstanding portion 47^a to which a toy catcher figure is adapted to be detachably secured. The lug 47 has a pin hole extending therethrough whereby the lug may be secured to the playing field in a desired pivoted position. The catcher figure is formed from a spring clip consisting of the two clamping jaws 48 and 49 pivoted together adjacent their medial portions, the U-shaped bar spring 50 acting between the upper inner sides of the clamping jaws 48 and 49 and being held from removal in position by a small flange at the upper end of clamping jaw 49, and a basket 51 horizontally pivoted to forward projections on the jaw 49 and made to simulate the arms of a catcher. The spring clip formed by the clamping jaws 48 and 49 is adapted to be detachably secured to the upstanding portion of the lug 47 so that the two jaws 48

and 49 clamp against the same. By pivoting the lug 47 to the plate 46 the catcher can be so turned that the basket 51 can be placed at varying positions behind the home plate to 5 catch a pitched ball thrown by the pitcher. An opening is provided in the central rear side of the basket 51 so that as a ball strikes the basket, two points of the ball will generally hit the same and there will thus be 10 very little rebound to the ball.

A bell crank lever 52 is pivoted to the plate 46 at one side of the home plate. One of the arms of the bell crank lever is provided with an upstanding lug 52^a while the other arm 15 thereof is connected to one end of a link 53 secured at its other end to the outer end of a lever 54 pivoted at its inner end to the plate 46. A coiled tension spring 55 is secured at one end to the link arm of the bell 20 crank lever 52 and is fixed at its other end to an up-struck hook 46^a on the plate 46. The toy batter figure is formed from a spring clip similar to the spring clip forming a portion of the catcher and includes clamping jaws 56 25 and 57 pivoted together and normally being adapted to be held together by the U-shaped bar spring 58 situated above the said pivot and being held in place by a flange formed at the top of the jaw 57. An angular plate 59 30 is secured by nutted bolt 60 to a projecting ear at the forward side of jaw 57 and a bat 61 is secured at its inner end between the angular plate 59 and the jaw 57 by means of the bolt 60. A lip is provided at the outer 35 end of angular plate 59 against which the nut of bolt 60 is adapted to abut to hold the same from rotation as the bolt proper is turned. By unloosening the bolt 60 from its nut the bat 61 can be raised or lowered as desired to 40 situate the outer end thereof at various heights in respect to the home plate. The spring clip formed by the clamping jaws 56 and 57 may be detachably engaged with the lug 52^a by pressing the two upper ends of 45 the jaws together and placing the lower ends of the jaws over the lug 52^a whereupon by releasing the jaws the spring 58 will cause the same to tightly clamp against the lug 52^a. To impart batting like action to the batter, 50 considering the parts to be in the position indicated in full lines Figs. 1 and 10, the operator will grasp lever 54 and will swing the same and parts connected thereto to the position illustrated in dotted lines Fig. 10. The bell crank lever 52 and the batter connected thereto will then be held under spring tension to swing the bell crank forwardly. The lever 54 will then be released, whereupon 55 the spring will rapidly force the bell crank lever forwardly thereby imparting a batting action to the batter and causing the bat 61 to be swung across the home plate. The forward movement of lever 54 will be limited by an upstruck lug 62 formed in plate 46.

65 A back stop 63 of considerable height and

formed from card board or similar sheet material may be detachably held behind the home plate against the home plate corner flanges 22 by means of lugs 64. The said back stop will act to catch foul balls and will 70 assist in confining the ball to the playing field.

Although various games may be played with the present invention the same is particularly adapted for playing the game of baseball. The game may be played according to the established rules of the national game modified to suit the requirements of a miniature ball game. Either one or more operators 75 may play the game. If two are playing the game, one will control the pitcher at a given time while another will control the batter. It will be the object of the pitcher operator to so cause the ball to be pitched as to deceive the batter operator and to prevent him from operating the batting mechanism to hit the ball. On the other hand, it will be the object of the operator of the batter to operate the batting mechanism to hit the ball as pitched and make 80 as many runs as possible. As the ball is pitched, the operator of the batter will release the batting mechanism to cause the batter to strike at the ball. If the ball is hit and comes to rest within the diamond 23 or within any 85 of the various pockets 25, the batter is considered to have made a base hit and a base runner 29 will be used for indicating positions of various base runners on the bases. If the ball when hit lights in one of the pockets 90 formed by the infielders and outfielders 27, the batter will be considered to be out. If the ball lights within the foul space 24 a foul ball will 95 be called on the batter. Due to the fact that the ball 45 is of cubical shape with rounded 100 edges the same will not roll or bounce to any great extent after being hit and the ball will thus be retained on the playing field.

When it is desired to put the game away, the batter and catcher may be readily removed from the playing field by pressing the upper 105 ends of the clamping jaws 48 and 49 and 56 and 57 respectively together, thereby releasing the clamping jaws from the lugs 47^a and 52^a respectively. The basket 51 of the catcher can then be swung over the top of the spring 110 clip and the two players can be stowed away in a very small space. To detach the pitcher from the playing field, the hook 34 will be unlatched from the latch 31^b, whereupon the bracket 35 may be removed from the aperture 115 31^c in plate 31. The various infielders and outfielders can be removed from the studs 36 by forcing the studs out of the keyways 120 formed in the players 27. The base runners 29 are, of course, bodily removable from the playing field. All the parts when removed 125 may be packed in a very small space and the parts can be removed or set up in very short order.

Practically all the parts of the device can 130

be stamped out from sheet material and, accordingly, the apparatus can be very quickly and cheaply made.

A toy game will be provided which in addition to affording keen amusement, will require considerable skill to play.

It will, of course, be understood that various changes may be made in the form, details, arrangement and proportions of the various parts without departing from the scope of the present invention.

What is claimed is:

1. In a toy baseball game, a detachable batter comprising a pair of clamp arms pivoted together and a spring normally forcing said clamp arms towards each other to engage a fixed support, whereby said clamp arms can be detachably engaged from the support, and a bat carried by said clamp arms.
2. In a toy ball game apparatus, an upstanding vertically pivoted lug adapted to be turned in one direction to put the same under spring tension to turn in an opposite direction, a spring clip forming the body portion of a toy batter figure, and releasably engageable with said lug and a bat carried by said toy figure.
3. In a toy baseball game apparatus, a vertically pivoted bell crank lever having an upturned end formed on one of the arms thereof, a coiled spring fixed at one end and secured at its other end to the other arm of said lever, a spring clip forming the body portion of a batter and adapted to be releasably engaged with the upturned portion of the said first mentioned arm and a bat carried by said spring clip whereby as said lever is moved in one direction against the tension of said spring and released, said spring will act to impart batting like movement to said batter.
4. The structure defined in claim 3, said bat being adjustable to position the outer end thereof at various heights in respect to said spring clip.
5. In a toy baseball game apparatus, a batter comprising a substantially vertical upstanding portion having a portion at its upper end of substantially angular shape in horizontal cross section, an angular plate fitting against said angular portion on the inner side thereof and having an inturned lip at its outer end, said portion and said plate being apertured to receive a bolt, a bat positioned between said member and said plate and also having a bolt aperture therein, and a nutted bolt extending through the apertures of all said members, the outer surface of the nut of said bolt being adapted to strike the lip of said plate to hold the nut from rotation as the bolt is turned, whereby said nut can be loosened and tightened to position said bat at various angles with said member.
6. In a toy ball game apparatus, a playing field and a catcher adapted to catch a pitched ball, said catcher comprising an upstanding

lug secured to said playing field, a spring clip forming the body of said catcher and adapted to be releasably engaged with said lug, and arms secured to said spring clip and forming a basket for catching a ball, whereby said catcher can be attached to or removed from said playing field.

7. The structure defined in claim 6, said arms being pivotally connected to said spring clip, whereby the same may be swung upwardly to lie substantially in the same plane as said spring clip.

8. The combination in a toy ball game apparatus, of a catcher adapted to catch a pitched ball and comprising an upstanding lug, said lug being eccentrically pivoted on said playing field for turning movement in a horizontal plane in respect to the field, a spring clip adapted to be releasably engaged with said lug to extend upwardly therefrom, said spring clip forming the body portion of a catcher and catcher arms pivoted to said clip to form a pocket for catching and retaining the ball, said spring clip being detachably engageable with said lug.

9. In a toy ball game apparatus, a pitching mound, a plate pivoted thereto and adapted to be turned about said pivot in a horizontal plane and secured in a desired position, a pitcher adapted to be secured to said plate and means for operating said pitcher to cause the same to pitch a ball.

10. In a toy ball game apparatus, a pitching mound, a pitcher holding plate mounted on said mound, said plate having an irregular shaped slot formed therein and an upwardly bent portion at one side of said slot forming a latch, a pitcher figure having an irregular shaped base portion matching with the irregular shaped slot and detachably fitting therein, a pivoted hook secured to said plate and adapted to be swung over said base portion to project into said latch, and means for operating said figure to cause the same to pitch a ball.

11. In a toy ball game apparatus, a plate having a shoulder formed thereon, a vertical portion upstanding from said plate, a pitcher body portion pivoted to said vertical portion, a ball carrying arm secured to said body portion adjacent its upper end, a lever pivoted at one end to the lower end of said body portion, said lever having a projecting tooth adapted to be engaged with said shoulder when the ball carrying arm of said body portion is rearwardly swung about said pivot, a torsion coiled spring for putting said body portion under tension when rearwardly swung and a trigger for disengaging said lever from said shoulder to allow said spring to act to carry the body portion forwardly and give pitching action to said arm.

12. The structure defined in claim 11, said body portion having a plurality of spaced upstanding portions with any one of which

one end of said spring is adapted to be engaged to variably tension the said spring.

13. In a toy ball game apparatus, a playing field, a pitcher adapted to pitch a ball, a batter adapted to bat the ball and a plurality of players situated in the field, each of said players being formed from sheet material and having a flat bottom portion adapted to be secured to the bottom of the field, an upwardly and rearwardly inclined portion at the rear of said bottom portion, and side and front portions extending upwardly from said bottom portion a short distance, said players being adapted to form pockets for catching 10 batted balls.

14. The structure defined in claim 13, said field players being detachable from the playing field.

15. The structure defined in claim 13, each 20 of said field players having a key-way formed on the bottom thereof for releasable engagement with studs projecting from said playing field.

16. In a toy ball game apparatus, an upwardly pivoted lug adapted to be turned in one direction to put the same under 25

spring tension to turn in an opposite direction, means forming the body portion of a toy batter figure and releasably and frictionally engageable with said lug and a bat 30 carried by said toy figure.

17. In a toy ball game apparatus, a playing field and a catcher adapted to catch a pitched ball, said catcher comprising an upwardly pivoted lug secured to said playing field, a member forming the body of said catcher and adapted to be releasably and frictionally engaged with said lug, and arms secured to said member and forming a basket for catching a ball, whereby said catcher can be attached 35 to or removed from said playing field.

18. In a toy ball game apparatus, a playing field, a pitcher holding plate mounted on said field, latch securing means on said plate, a pitcher figure having a base portion adapted 40 to be releasably secured in said latch securing means, and means for operating said pitcher figure to cause the same to pitch a ball.

In testimony whereof I affix my signature.

JOHN A. EKELUND.
